United States Patent Office

Des. 213,764
Patented Apr. 8, 1969

213,764

JUG

James E. Plummer, Toledo, Ohio, assignor to Owens-Illinois, Inc., a corporation of Ohio

Filed June 13, 1968, Ser. No. 12,343

Term of patent 14 years

Int. Cl. D9—01

U.S. Cl. D9—48

FIG. 1

FIG. 2

FIG. 3

FIG. 4

FIGURE 1 is an elevational view of a jug showing my new design, the opposite side being a mirror image of the side shown;

FIGURE 2 is an elevational view looking from the right of FIG. 1;

FIGURE 3 is a top plan view; and

FIGURE 4 is an elevational view looking from the left of FIG. 1.

The characteristic features of the design reside in the portions shown in full lines.

I claim:

The ornamental design for a jug, substantially as shown and described.
